cent to C. Archer Smith

Application May 26, 1943, Serial No. 488,619

16 Claims. (Cl. 123—90)

This invention relates to a mechanical compensator usable to provide for relative adjustment between two main parts and for transmitting a load between the main parts. The parts are so constructed that when a load is applied which tends to force the two main parts toward each other, the compensator automatically locks and carries the load, but when the load is removed, the compensator unlocks, and if the two main parts are then moved relative to each other, the compensator automatically adjusts itself to the new positions of the main parts. If the load is now reapplied, the compensator again locks and assumes the load in its new position.

A particular object of the invention is to provide a simple and reliable device capable of maintaining a clearance-free fit between mechanical parts regardless of wear or of changes in size of the parts due to temperature variations.

My Patent No. 2,326,780, filed June 25, 1941, discloses a mechanical compensator which incorporates certain new principles of construction and operation. The present invention utilizes those same principles, but in a manner which attains the same results with a smaller number of parts and in a narrower space.

A typical installation involves the use of the device as an automatic tappet to provide at all times a clearance-free drive for the valves of an internal combustion engine. In such use the device is installed in place of the usual tappet and is capable of automatic lengthening to compensate for any wear or shortening of the parts; of automatic locking on each lift of the valve cam so as to positively open the valve; and of automatic unlocking on each stroke to permit shortening of the device to accommodate lengthening of the parts due to heat expansion. These results are achieved with a minimum number of simple, reliable parts located within a tappet body so that the automatic tappet has substantially the same external appearance as a solid tappet.

These and other objects and advantages of the invention will become apparent as the description proceeds.

While preferred forms are disclosed herein for purposes of illustration, it should be understood that various changes in the construction and arrangement of parts may be made without departing from the spirit of the invention.

In the drawing:

Figure 1 is a longitudinal section through a preferred form of the invention showing related parts, the adjustment device being in its fully extended position.

Figure 2 is a view similar to Figure 1, but showing the parts in an intermediate or starting position.

Figure 3 is a view similar to Figure 1, but showing the adjustment device in fully retracted position.

Figure 4 is an exploded view showing isometrically the operating parts of Figure 1.

Figure 5 is a cross section taken on line 5—5 of Figure 2.

Figure 6 is a cross section taken on line 6—6 of Figure 2.

Figure 7 is a longitudinal section similar to Figure 2 but showing a modification.

Figure 8 is a cross section similar to Figure 6 but showing a further modification.

In a presently preferred form of the invention, shown in Figures 1 to 6, the tappet housing 10 is cylindrical on the exterior and is formed with a cylindrical bore 11. Within the bore and resting on the bottom wall thereof is a lower pressure body 12, the main portion of which is approximately in the form of part of a cylinder with a flat inner face 13 and a flat bottom face 14. The upper end has an upwardly facing flat cam face 15 which slopes inwardly and downwardly to join the inner face 13.

The plunger 16, which forms the compensating member, has a main body which is semi-circular in cross section, with an outer curved wall 17 and an inner flat face 18. At its lower end plunger 16 carries an inward projection 19 formed with an inwardly and downwardly sloping flat cam face 20 which faces upwardly. At a point about intermediate its ends plunger 16 carries an inward projection 21 formed with an inwardly and downwardly sloping cam face 22 which faces upwardly and with an inwardly and upwardly sloping cam face 23 which faces downwardly.

The floating separator 24, which is located opposite plunger 16 and between the lower projection 19 and the intermediate projection 20, is partly cylindrical in form, having a flat face 25 which engages inner flat face 18 of plunger 16, and also having flat top and bottom faces 26 and 27.

The intermediate pressure body 28, which is located opposite intermediate projection 21 of plunger 16, is also partly cylindrical in form and has an inwardly and downwardly sloping cam face 29 which faces upwardly, and an inwardly and upwardly sloping cam face 30 which faces downwardly.

The top pressure body 31 includes a partly cylindrical portion 32 which has a flat bottom

face 33 and a reduced upward extension 34. The cylindrical portion 32 and the reduced extension 34 both carry a flat face 35 which engages inner flat face 18 of plunger 16.

Suitable pressure transmitting devices are arranged to cooperate with the several cam faces described above. One form of device which is capable of transmitting considerable pressure with minimum friction is the roller, which is used in the preferred form of compensator. Only three rollers are used, the roller 36 cooperating with the lower flat face 27 of floating separator 24 and with cam faces 15 and 20, the roller 37 cooperating with the upper flat face 26 of floating separator 24 and with cam faces 23 and 30, and the roller 38 cooperating with lower flat face 33 of top pressure body 31, and with cam faces 22 and 29.

The plunger 16 is biased upwardly by a take-up spring 39 which is guided by a stem 40 projecting downwardly from the plunger, while upward movement of the parts is limited by a split retainer ring 41. All parts of the unit are formed of a strong material such as a suitable steel.

In Figures 1, 2 and 3 the valve-operating cam is indicated at 42, the valve stem at 43, and the valve spring at 44.

Installation

Figure 1 illustrates the position of the parts of the tappet when the unit is in fully extended position ready for installation.

In making the installation the valve stem 43 is lifted or removed, in the usual manner, and the automatic tappet is so dimensioned that when the valve spring 44 is released the valve stem 43 engages the end of extension 34 with the full force of the valve spring. This force immediately locks the automatic tappet in the position of Figure 1 in a manner that will be explained subsequently.

It will be noted that in the position of Figure 1 the extension 45 of the plunger 16 projects above the top of housing 10. This projecting end 45 serves as a trigger for tripping the locking mechanism. Tripping is done by merely applying a relatively light downward pressure to the end of projection 45, whereupon the tappet ceases to resist the downward pressure of valve spring 44 and the parts readjust themselves to the normal starting position illustrated in Figure 2. In this position the lower end of the tappet housing 10 is resting on the heel of cam 42; the valve is pressed against its seat by the full force of the valve spring minus the light counter-pressure of the take-up spring 39; the spring 39 is resiliently expanding the tappet to maintain it in direct contact with both cam 42 and valve stem 43; and there is no free clearance permitted anywhere between cam and valve stem.

It is believed that the present improved automatic tappet operates in the manner explained in my prior co-pending Patent No. 2,326,780 referred to above, but in order to make the correspondence of parts perfectly clear the explanation will be repeated with particular reference to the parts as disclosed herein.

Action in taking up clearance

The action of the automatic tappet in eliminating all clearance, either initially or whenever clearance might tend to arise for any cause, such as wear or changes due to thermal conditions, takes place as follows:

Take-up spring 39 forces compensating member 16 upwardly, and the upward movement of

cam face 22 formed on the intermediate projection 21 forces roller 38 to roll toward the right (as viewed in Figure 2) and outwardly on cam face 29.

During this upward movement of plunger 16 the intermediate pressure body 28 remains stationary. This is because lower pressure body 12 remains seated on the bottom of bore 11; cam face 20 causes roller 36 to move toward the right and upwardly on cam face 15; but cam face 23 moves upward the same distance as cam face 20 and permits roller 37 to move to the left and upwardly along cam face 30. Thus while upward movement of roller 36 causes upward movement of floating separator 24, which in turn pushes roller 37 upward, movement of roller 37 toward the left along cam face 30 prevents this roller from moving pressure body 28 upwardly.

Since intermediate pressure body 28 remains stationary, the upward movement of compensating member 16 causes roller 38 to move toward the right and upwardly on cam face 29, thus causing upward movement of the top pressure body 31. This movement continues until all clearance has been taken up, i. e., all points of contact from cam 42 to valve stem 43 are snugly engaged under pressure derived from the take-up spring 39.

Because the roller 38 is moved upwardly by co-action of cam faces 22 and 29 to cause compensating movement of top pressure body 31, these cam faces may be called "compensating" cam faces.

During this action of taking up clearance the parts move from their positions in Figure 2 toward their positions in Figure 1, the latter view illustrating the positions of the parts after the tappet has reached its extreme limit of outward extension. Since the projecting upper end 45 of plunger 16 also moves up, it may serve as a visual indicator of the fact that the tappet has reached its outer limit of extension. Thus, a shoulder 46 may be so formed as to come flush with the top of body 10 when the parts are in the position of Figure 1.

Locking action in assuming load

As soon as the cam 42 begins to apply pressure to the lower end of the tappet housing 10, the parts of the tappet are subjected to external pressure which causes the tappet to lock automatically in substantially the position illustrated in Figure 2.

Experiments have proved that the upper roller 38 is not involved in this locking action, and it is believed the locking action can most readily be explained by considering what occurs when the lower pressure body 12 and the intermediate pressure body 28 are forced toward each other. When this happens the cam surface 15 on the lower pressure body and the cam surface 30 on the intermediate pressure body form opposite walls of a constrictable wedge groove which, while being constricted, forces the lower roller 36 and the middle roller 37 against the floating separator 24 and against the cam faces 20 and 23 of the plunger 16. Since these latter faces are formed on parts integral with the plunger they cannot separate and form opposite walls of a fixed wedge groove, the resistance of which causes the plunger 16, floating separator 24, and rollers 36 and 37 to become firmly locked as a single unit wedged between the sloping walls of the constrictable wedge groove.

The wedging force just described is sufficient to resist any downward movement of plunger 16 under load applied to the plunger through the upper roller 38. This is apparently due to the fact that the upper roller 38 divides its downward pressure equally between the intermediate pressure body 28 and the plunger 16 (the angles of cam faces 22 and 29 being equal), hence the force applied to maintain the wedging action just described is equal to the force tending to move plunger 16 downwardly.

But when additional force is applied directly to plunger 16 by pressing down on the extension 45 in the manner previously described, the balance of forces is destroyed and the wedge lock is broken, permitting the plunger to move down.

However, barring such external interference with the wedge lock, the locking force is proportionate to the load applied to the tappet, and hence the device can positively transmit any load within the mechanical strength of the material of the parts.

Compensating for lengthening of valve parts

The automatic tappet also compensates for downward movement of the valve stem 43 toward cam 42 such as might result from expansion of the valve stem under increased temperature. This compensation occurs in the following manner.

When the tappet is placed under an external load, as recited in the previous section, the first part of the pressure is taken up by elastic deformation of the parts, which, in a typical case, permits the tappet to yield to the extent of approximately 0.001 inch up to the time the full load is assumed. This downward movement of 0.001 inch of the top pressure body 31 is transmitted downwardly through the top roller 38 and since this roller is supported equally on intermediate pressure body 28 and intermediate projection 21 of plunger 16, a downward movement of approximately 0.001 inch is transmitted to intermediate pressure body 28 and to plunger 16. At this point, that is, after all parts have been deformed to the full extent required by the load applied, the wedge lock previously explained becomes effective and there is no further yield of the tappet as it transmits the force of the cam to the valve.

When the load on the tappet is removed, the wedge lock is released, and it has been found that this unlocking takes place before the tappet has resiliently expanded to its original over-all length.

Apparently the reason for this occurrence is that during the time the last part of the load is being removed (the part that on application of the load caused an elastic deformation of 0.001 inch) the elastic return (release of elastic deformation) causes the intermediate pressure body 28 to move upward slightly relative to plunger 16, thus causing roller 38 to roll over against cam face 22. At this instant the top pressure body 31 is still being biased downwardly by a last part of the external load that is stronger than spring 39 and hence this outward movement of roller 38 follows the line of least resistance and moves plunger 16 downward, releasing the wedge lock.

The slight upward movement of intermediate pressure body 28 just mentioned is believed to result from the fact that when the tappet is under load, the load compresses a column which can be visualized in Figure 2 as including the lower pressure body 12, lower roller 36, floating separator 24, intermediate roller 37, intermediate pressure

body 28, and upper roller 38. Elastic return acts mainly to permit a lengthening of this column, moving the intermediate pressure body 28 upwardly with the unlocking result previously explained.

As for the elastic return of the parts that react between the lower projection 19 and intermediate projection 21 of plunger 16, the upward reaction of middle roller 37 on projection 21 appears to be exactly balanced by the downward reaction of the lower roller 36 on the lower projection 19, hence these forces cancel each other.

It has been found that one-half of the upward movement of intermediate pressure body 28 is utilized to move plunger 16 downward and the other half is translated into upward movement of the top pressure body 31. The result is that the unit unlocks when one-half of the total elastic deformation has been released, so that while the tappet underwent an elastic deformation 0.001 inch when assuming the load, in the unloading action the plunger 16 unlocks when the unit has undergone an over-all elastic return of only about 0.0005 inch.

The unit could, therefore, be 0.0005 inch shorter than it was originally, and if no change in position of the lower end of the valve stem has taken place there would be a tendency for a clearance of 0.0005 inch to appear between the valve stem and the tappet. But this slight amount of potential clearance is kept from developing into actual clearance by take-up spring 39 pressing plunger 16 upwardly to operate the parts in the manner previously explained under the heading "Action in taking up clearance."

If instead, the lower end of the valve stem has assumed a new position nearer to cam 42, such as might result from thermal expansion of the valve stem, the unlocking action just explained permits the top pressure body to be held down to a new position somewhat lower than its original position, within the 0.0005 inch potential clearance.

It can be seen therefore, that at the end of each load stroke the unit unlocks at a length 0.0005 inch shorter than it was on the previous stroke and that the tappet can accommodate itself on each stroke to an increase of 0.0005 inch in the length of the related parts. This back-off of the tappet is due to the action of elastic return in unlocking the parts, so it may appropriately be called "elastic back-off."

The tappet can continue to shorten in this manner until it reaches the fully retracted position of Figure 3, in which the stem 40 is touching the bottom of the bore in housing 10. In this position the upper end of extension 45 of plunger 16 is flush with the top of housing 10, thus giving a signal that the tappet has reached its limit of accommodation in this direction.

It should be clear from the above explanation that the parts operate to lengthen the tappet if necessary to take up clearance; that its locking parts provide a positive drive when external pressure is applied; and that the "elastic back-off" permits the tappet to shorten if the end of the valve stem moves closer to the cam. Because all of these actions take place within the tappet in response to external conditions, the unit is entirely self-contained and self-operating and is truly "automatic," requiring no additional parts such as oil supply systems, inertia members, or operating rods. It therefore can be installed as easily as a conventional solid tappet.

In the above description the improved tappet

has been set forth as used in a conventional L-head internal combustion engine, but it is of course equally adapted for the operation of overhead or any other type of valves, and for all other types of mechanical linkage where it is desired to eliminate clearance. And while the unit has been illustrated in a vertical position it can be used in any desired position.

Modifications can be made in various parts of the unit. Thus some variation can be made in the angle of the cam faces, which are illustrated at 45° to the vertical axis of the unit, although all cam faces should be at the same angle.

In comparing the details of the compensator disclosed herein with those disclosed in my co-pending Patent No. 2,326,780, it will be noted that the forms of the present application have fewer parts, since only three pressure-transmitting members are used, and that the compensator can be made with a smaller over-all diameter. This is because each of the parts, except for the rollers, is partly cylindrical, i. e., it extends only partly across the cylindrical bore and is complemented by another part to fill the cylindrical bore. The parts can therefore be given adequate size and strength with a smaller diameter than where certain of the parts must extend entirely around the periphery of a circular or other shaped bore.

Reference has already been made to the fact that in the preferred form rollers are used because they can transmit pressure with a minimum of frictional resistance. But in cases where more contact area is desired and a slight additional amount of frictional resistance can be tolerated the rollers may be replaced by sliding blocks such as illustrated at 36a, 37a and 38a in Figure 7. Each of these sliding blocks has a face at right angles to the vertical axis of the unit and two faces at the same angle as the cam faces on which they ride, being therefore generally triangular in form. The rollers, sliding blocks, or other equivalent devices are comprehended in the term "pressure transmitting devices" as used in the appended claims.

Another possible modification is in the shape of the bore in the housing and of the cooperating surfaces of the operating parts. In the forms above described the bore is cylindrical and the surfaces of the operating parts in contact with the bore have the contour of part of a cylinder. While this cylindrical form appears to be most economical to manufacture at the present time, it is quite possible to use some other shape, such as the square form illustrated in Figure 8. In this case the bore of the housing is square in cross section and the outside of the working parts have a corresponding contour with one flat face parallel to the axes of the pressure-transmitting devices.

The housing is important only as supplying a wall to guide the operating parts and to hold them assembled during installation of the unit, and hence it may be dispensed with if the unit is to be installed in a bore in some other part.

I claim:

1. In a mechanical compensator of the type having a part formed with a bore of uniform diameter, a lower pressure body, an intermediate pressure body, a top pressure body, a compensating member, means biasing the compensating member toward the top pressure body, and means for transmitting pressure and movement between said parts, the improvement comprising: each of said lower, intermediate and top pressure bodies

and the compensating member having a smooth wall in direct sliding engagement with the wall of the said bore.

2. A compensator as specified in claim 1 but in which the bore is square in cross section and the said pressure bodies and compensating member have their outer walls conforming to the square section.

3. In a mechanical compensator of the type having a part formed with a bore, a lower pressure body, an intermediate pressure body, a top pressure body, a compensating member, means biasing the compensating member toward the top pressure body, and means for transmitting pressure and movement between said parts, the improvement comprising: each of said lower and intermediate pressure bodies having an over-all lateral extent less than the diameter of said bore and being complemented by a portion of the compensating member to substantially fill the cross section of the bore.

4. In a mechanical compensator of the type having a part formed with a cylindrical bore, a lower pressure body, an intermediate pressure body, a top pressure body, a compensating member, means biasing the compensating member toward the top pressure body, and pressure-transmitting devices for transmitting pressure and movement between said parts, all of the parts being within said bore, the improvement which comprises: each of said lower and intermediate pressure bodies and said compensating member having a curved outer wall in contact with the wall of said cylindrical bore, and a straight part extending on a chord of said cylindrical bore.

5. In a mechanical compensator of the type having a part formed with a cylindrical bore, a lower pressure body, an intermediate pressure body, a top pressure body, a compensating member, means biasing the compensating member toward the top pressure body, and pressure-transmitting devices for transmitting pressure and movement between said parts, a floating separator located between some of the pressure-transmitting devices, the improvement which comprises: the compensating member having a curved outer wall in contact with said cylindrical wall and having flat inner faces; each of said lower pressure body and the floating separator having a curved outer wall in contact with said cylindrical bore and having a flat inner face cooperating with a flat face of the compensating member.

6. In a mechanical compensator of the type having a housing formed with a bore, a lower pressure body, an intermediate pressure body, a top pressure body, a compensating member, means biasing the compensating member toward the top pressure body, and means for transmitting pressure and movement between said parts, the improvement comprising: an extension on the compensating member, said extension projecting to the end of the housing and being accessible and visible from the exterior of the housing.

7. In a mechanical compensator of the type having a housing formed with a bore; a top pressure body; a compensating member; means biasing the compensating member toward the top pressure body and tending to increase the distance between the top and lower pressure bodies; means operable to lock the compensating member against movement when the top and lower pressure bodies are pressed together by external load, the locking means being unlockable by an external force moving the compensating member downward; the improvement comprising: an up-

ward extension on the compensating member, said extension projecting to the end of the housing and being accessible from the exterior of the housing for application of unlocking force to the compensating member.

8. In a mechanical compensator of the type having a top pressure body, a compensating member, means biasing the compensating member toward the top pressure body to cause compensating movement of the top pressure body, and means to lock the compensating member against movement, the improvement comprising: a single roller serving to transmit compensating movement to the top pressure body.

9. In a locking device for locking two parts movable relative to each other, of the type having oppositely inclined cam surfaces on one of said movable parts forming sides of a fixed wedge groove, oppositely inclined cam surfaces carried by the other of said movable parts forming sides of a constrictable wedge groove, a floating separator intersecting the fixed and constrictable wedge grooves, pressure-transmitting means contacting the upper and lower sides of the floating separator, the improvement comprising: a single roller serving as the pressure-transmitting means in contact with the upper side of the floating separator, and a single roller serving as the pressure-transmitting means in contact with the lower side of the floating separator.

10. In a mechanical compensator of the type having a top pressure body, a compensating member, means biasing the compensating member toward the top pressure body to cause compensating movement of the top pressure body, and means to lock the compensating member against movement, the improvement comprising: a single pressure-transmitting device of generally triangular form serving to transmit compensating movement to the top pressure body.

11. In a locking device for locking two parts movable relative to each other, of the type having oppositely inclined cam surfaces on one of said movable parts forming sides of a fixed wedge groove, oppositely inclined cam surfaces carried by the other of said movable parts forming sides of a constrictable wedge groove, a floating separator intersecting the fixed and constrictable wedge grooves, pressure-transmitting means contacting the upper and lower sides of the floating separator, the improvement comprising: each of said pressure-transmitting means being in the form of a generally triangular block.

12. In a mechanical compensator of the type having a housing formed with a bore; a top pressure body; a compensating member; means biasing the compensating member toward the top pressure body; means translating upward movement of the compensating member into upward movement of the top pressure body; means operable to lock the compensating member against downward movement when the top and lower pressure bodies are pressed together by external load, the locking means being unlockable by an external force moving the compensating member downward; the improvement comprising: an upward extension on the compensating member, said extension projecting to the end of the housing and being accessible from outside the housing for application of unlocking force to the compensating member, said extension also being visible from outside the housing to indicate the position of the compensating member.

13. A mechanical compensator comprising: a part formed with a bore; a compensating mem-

ber having two oppositely sloping cam faces forming sides of a fixed wedge groove and carrying a compensating cam face; a lower pressure body and an intermediate pressure body which respectively have oppositely sloping cam faces forming sides of a constrictable wedge groove; a floating separator intersecting the fixed and constrictable wedge groove, said separator having flat top and bottom faces; first and second pressure-transmitting members in contact with the flat faces of the floating separator respectively and contacting the cam faces forming the fixed and restrictable wedge grooves; the intermediate pressure body carrying a compensating cam face; a top pressure body having a flat face on its lower side; a third pressure-transmitting member contacting said flat face of the top pressure body, the compensating cam face of the compensating member, and the compensating cam face of the intermediate pressure body; and means biasing the compensating member toward the top pressure body; the compensating member, the lower pressure body, the floating separator, the intermediate pressure body and the top pressure body each having a smooth wall in sliding engagement with the wall of said bore.

14. A compensator as specified in claim 13 but in which the said bore is square in cross section and the parts contacting the wall of the bore are shaped to conform to said square shape.

15. A mechanical compensator comprising: a part formed with a bore; a compensating member having two oppositely sloping flat cam faces forming sides of a fixed wedge groove and carrying a flat compensating cam face; a lower pressure body and an intermediate pressure body which respectively have oppositely sloping flat cam faces forming sides of a constrictable wedge groove; a floating separator intersecting the fixed and constrictable wedge grooves, said separator having flat top and bottom faces; first and second pressure-transmitting members in contact with the flat faces of the floating separator respectively, and contacting the cam faces forming the fixed and restrictable wedge grooves; the intermediate pressure body carrying a flat compensating cam face; a top pressure body having a flat face on its under side; a third pressure-transmitting member contacting said flat face of the top pressure body, the compensating cam face of the compensating member, and the compensating cam face of the intermediate pressure body; and means biasing the compensating member toward the top pressure body; the compensating member having an outer wall conforming to and in contact with the wall of said bore, and having flat inner faces; each of said lower and upper pressure bodies and the floating separator having outer walls conforming to and in contact with the wall of said bore, and having a flat inner face cooperating with a flat face of the compensating member.

16. A mechanical compensator comprising a housing formed with a cylindrical bore; a compensating member having a lower projection with an upwardly facing flat cam face, an intermediate projection with a downwardly facing flat cam face and an upwardly facing flat cam face, and an upward extension; a lower pressure body resting on the bottom wall of the bore and having an upwardly facing flat cam face; a floating separator located above the lower pressure body and having flat top and bottom faces disposed at right angles to the vertical axis of the compensator; an intermediate pressure body located above the

floating separator and having a downwardly facing flat cam face and an upwardly facing flat cam face; a top pressure body located above the intermediate pressure body and having a reduced upper extension and having a flat face on its under side; means biasing the compensating member toward the top pressure body; a first pressure-transmitting member contacting the cam face of the lower pressure body, the cam face of the lower projection of the compensating member, and the flat bottom face of the floating separator; a second pressure-transmitting member contacting the flat top face of the floating separator, the downwardly facing cam face of the intermediate pressure body, and the downwardly facing cam face of the compensating member; a third pressure-transmitting member contacting

the upwardly facing cam face of the intermediate pressure body, the compensating cam face of the compensating member, and the flat lower face of the top pressure body; and means biasing the compensating member toward the top pressure body; the compensating member having an outer curved wall conforming to and in contact with the wall of said bore, and having flat inner faces; each of said lower, intermediate, and upper pressure bodies and the floating separator having outer curved walls conforming to and in contact with the wall of said bore; each of said lower and upper pressure bodies and the floating separator having a flat inner face cooperating with the flat face of the compensating member.

WILLIAM C. HOWARD, JR.
